(57) **CLAIM**

The ornamental design for a fabric cane cover, as shown and described.

DESCRIPTION

FIG. 1 is a side perspective view of a fabric cane cover, with a cane, showing my new design;

FIG. 2 is a front elevational view of the fabric cane cover showing without the cane;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines are shown in the drawings for illustrative purposes only and form no part of the claimed design.
